PERIODIC CIRCUIT BREAKER WITH A LIQUID CONDUCTOR PARTICULARLY FOR CONTACT CURRENT CHANGERS

Marius Hugo Wilhelm Widakowich,
Stocksund, SwedenApplication April 6, 1945, Serial No. 586,914
In Sweden April 6, 1944

5 Claims. (Cl. 200—32)

1

The present invention relates to a periodic circuit breaker which is particularly intended to be used as a contact current changer for the conversion of alternating current into direct current, or vice versa, and wherein an electrically conducting liquid, preferably mercury, is employed as a conductor, while contact members are used for periodic closing and breaking of one or more circuits. The invention refers particularly to such circuit breakers of said type which consist of two receptacles holding the contact liquid and communicating with each other, said receptacles being arranged concentrically within one another, and one of which is stationary and the other rotatably mounted, the contact liquid being adapted to circulate through the receptacles in a manner to form a number of jets ejected from the one receptacle, said jets cooperating with peripheral contacts in the other receptacle. The invention is principally distinguished by the feature that the rotary receptacle is formed as a rotary pump, preferably as a centrifugal pump, to circulate the contact liquid through the two receptacles. By this means a compact construction of the circuit breaker is obtained, inasmuch as the circulation pump, which is otherwise necessary, is now dispensed with. The arrangement also involves the advantage that the circulation system may be housed, together with all of the contacts, within a closed vessel which is preferably constituted by the one receptacle, which is then preferably arranged to be stationary, whereas the other receptacle is rotatably mounted within said first-mentioned receptacle and adapted to be driven from an external source of power by means of a rotating magnetic field. If desired, the outer vessel may then be hermetically closed, and the circuit breaker may be adapted to operate in vacuum or in an atmosphere of a neutral gas, so that the contact breaking takes place without sparking, as far as possible.

The invention will be explained more closely with reference to the accompanying drawing, which by way of example illustrates a form of embodiment of a periodic circuit breaker in accordance with the invention. Figure 1 is a vertical section through the circuit breaker, and Figure 2 is a horizontal section on line 22 in Figure 1. Figure 3 shows a modified construction.

The circuit breaker comprises an outer stationary receptacle 1 of metal, preferably iron, and a receptacle 2 rotatably mounted within said first-mentioned receptacle and also consisting of iron. The outer receptacle 1 consists of a cylind-

2

rical portion 3 and a bottom portion provided with a downwardly extended central portion 4 and a draining hole closed by means of a threaded stopper 5. The two receptacles communicate with one another through a central hole 6 in the lower portion of the inner receptacle 2. The receptacles are filled with mercury which, when the apparatus is inoperative, takes about the level indicated by the dashed line 7. The inner receptacle is mounted by means of ball bearings 8, 9 on a central journal pin 10 screwed fast into a cover 11 of glass or other non-magnetic and electrically non-conducting material. The cover 11 is rigidly connected with the receptacle 1 and tightens against a flange 12 extending around the upper edge thereof. The ball bearings 8, 9 are enclosed within a cap 13 forming a cylindrical extension of a cover 14 covering the upper part of the inner receptacle while being rigidly united with the receptacle. The latter cover consists of magnetic material, preferably iron, and is provided with a number of pole pieces 15, the upper surfaces of which are located immediately underneath the cover 11. Rigidly arranged on a journal 16 coaxial with the pin 10 and situated above the cover 11 is a yoke 17 of iron, said yoke supporting a number of magnet cores corresponding to the pole pieces 15, said cores being provided with magnet windings 18. The parts 14, 15, 17 and 18 thus form a magnetic circuit through which the torque of the motor may be transmitted to the inner receptacle 2, which then rotates at the speed of the motor shaft. The pole pieces are surrounded by rings 20 of copper or other electrically conducting material said rings being adapted in known manner to facilitate the starting.

The inner receptacle 2 is of a downwardly tapering, substantially conical shape, and is provided on the inside thereof with a number of radially disposed partitions 21 adapted at the rotation to entrain the quantity of mercury flowing through the receptacle, the rotating receptacle then acting as a centrifugal pump, and the mercury entering from the outer receptacle to the inner one through the opening 6. In order to increase the impelling force acting upon the mercury, the lower parts of the radial partitions 21 may be obliquely positioned or curved so as to form buckets adapted to catch the mercury. The mercury will thus flow up along the wall of the receptacle through the action of the centrifugal force, a portion of the mercury then escaping through a number of apertures 22 provided in the wall, said apertures opening into ejecting nozzles

23. To ensure the discharge of a sufficient quantity of mercury through said nozzles, the receptacle is provided on the inside thereof with a projecting circularly extending edge 24 adapted to catch a portion of the mercury. The remainder of the mercury continues along the portion of the conical receptacle wall situated above the nozzles 23 and escapes through apertures 25 provided in the upper portion of the wall, the number of said apertures equaling that of the nozzles 23 and lying, in the example shown, in the same axial plane as the latter.

The mercury escaping downwardly through the upper openings 25 is received by channels 26 in a number of metallic contact members 27 arranged in an insulating manner on the inside of the cylindrical wall 3 of the receptacle 1, said contact members being electrically connected with contact clamps not shown in the drawing to make connection with the external circuits. The electric insulation between the contact members 27 and the outer receptacle wall 3 is constituted by a cylinder 28 of ceramic material, for example. The contact members 27 are formed as ejecting nozzles for a corresponding number of stationary connecting jets, and are to this end provided with a through passage 29, through which the mercury received in the channel 26 is discharged downwardly in the form of a compact jet passing as a single elongated jet through a recess or a free space 30 in the lower portion of the contact member. To facilitate the return of the mercury to the common collecting place in the bottom of the outer receptacle 2, without the jets then making contact with the mercury contained in the receptacle 1, there is provided a screen or channel 31 in the path of the jet, said screen or channel being adapted to catch the mercury jet and to cause the mercury on its passage through the perforation holes to be finely divided and transferred to the receptacle 1 in the form of a stream of particles or drops insulated from one another. The recesses 30 are open inwardly and situated on a level with the ejecting nozzles 23. The rotating connecting jets discharged from the latter ejecting nozzles will consequently penetrate into the space 30 so as to make contact with the stationary connecting jet discharged from the channel 29. To prevent non-desirable movements of the quantities of the mercury flowing into the space 30, there are provided through-holes 32 in the contact piece 27 and in the insulating wall 28 opposite the ejecting nozzles 23, through which the horizontal mercury jets may continue into an annular recess 33 in the wall 3, said recess opening through passages 34 adjacent to the bottom of the receptacle 1, so that the mercury may return this way to the lower portion of the receptacle. The annular recess 33 and the openings 32 are so arranged that no direct conducting connection may be produced between the contact pieces 27 and the outer receptacle 1, after the horizontal jet has moved during its rotation past the contact piece so as to break the contact therewith. The mercury quantities returning to the outer receptacle are collected in the downwardly extended central portion 4, from which the mercury is driven up into the inner receptacle through the influence of the centrifugal force, in the manner indicated hereinbefore. To prevent the mercury in the outer receptacle from being brought into rotation by the friction against the inner receptacle, radial partitions 40 may be provided in the outer receptacle. The inflow of the mercury through

the opening 8 may also take place through a tube fixed in the outer receptacle and connected to said opening, said tube tightening against the wall of the inner receptacle by means of a labyrinth packing or the like.

Provided between the contact pieces 27 and the glass cover 11 are distance members 35, which may be made from metal or from insulating material, and which in a suitable manner confine that space above the channel 28 in which the ejecting nozzles 25 are moving.

As will appear from Figure 2, the channels 26 extend, the same as the channels 29, approximately over the whole length of the contact pieces 27, the stationary jets then escaping from the channels 28 obtaining a corresponding width. Since the rotating jets discharged from the nozzles 23 are preferably thread-like, the length of the channel 28 in a peripheral direction will thus determine the length of the contact closing periods. In the example shown, it is assumed that the nozzles 23 and 25 are located opposite each other, contact closing thus taking place approximately at the same time between the feeding jet discharged from the nozzle 25 and the contact piece 27, on the one hand, and the stationary connecting jet and the rotating connecting jet discharged from the nozzle 23, on the other hand. After that, the contact is maintained both ways, until the feeding jet discharged from the nozzle 25 moves past the fore edge of an insulating screen 36, which is arranged over the end of the contact piece. The feeding of mercury into the channels 26 being then interrupted, the contact will now be maintained only by the rotary connecting jet discharged from the nozzle 23, as long as this jet makes contact with the stationary connecting jet. This ensures that contact breaking will always take place between two mercury jets and that, consequently, the breaking of the feeding jet at the edge of the insulating screen 36 may take place without sparking. The insulating screens 36 are so arranged as to cover the ends of two adjacent contact pieces 27, that edge of each individual screen which is remote in the direction of movement then determining the time for the closing of the current. By changing the position of said edge relatively to the channel, the length of the contact closing period may be varied.

The periodic circuit breaker may be arranged for the control of any desired number of external circuits by the arrangement of a corresponding number of contact pieces 27 about the inside of the outer receptacle. In the example shown, there are provided nine contact pieces of said type.

To prevent the mercury as far as possible from entering the ball bearing housing 13, there are provided labyrinth packings 37 between the covers 11 and 14, the lower pockets in said labyrinth packings then communicating through passages with the interior of the receptacle 2 for the purpose of deflecting mercury. The small quantities of mercury which might still penetrate into the bearing housing 13 are carried off through apertures 38 in the bottom of the bearing housing, and filters may then be provided above said apertures, so that the bearing oil is prevented from finding its way out through the apertures. Such means to prevent the mercury from penetrating into the bearing housing are believed to be superfluous, however, as the bearing housing 13 should permit of being filled with mercury, so

that the balls of the bearings are moving in mercury.

In order to prevent the feeding jets from disturbing the collection of mercury in the channels 26 on account of the velocity of such jets, whereby interruptions might occur in the jets escaping through the channels 29, it is possible, as shown in Figure 3, to provide a special distributing channel 39 between the nozzles 25 and the contact pieces 27, the mercury being then first caught by said channel, from which the mercury escapes immediately through apertures in the bottom of the channel, so that the mercury flows down into the channel 26 in a finely divided state, for instance in the form of fine jets or small drops. Said channel 39 may extend continuously about the whole circumference. In this case, the current will be closed and interrupted solely by the contact between the rotating jet escaping from the nozzle 23 and the stationary jet escaping through the channel 29.

I claim:

1. Periodic circuit breaker with a circulating contact liquid, particularly for contact current changers, characterized in that the circulation system comprises a stationary outer receptacle and a rotating inner receptacle serving as a circulation pump, said receptacles being provided with ejecting nozzles for the contact liquid, so arranged that the contact liquid is divided during its circulation into a system of rotating jets and a system of stationary jets, the rotating jets discharged from the ejecting nozzles of the inner receptacle being adapted periodically to make contact with the stationary jets discharged from a number of mutually insulated ejecting nozzles in the outer receptacle.

2. Periodic circuit breaker according to claim 1, characterized in that the rotary part serving as a circulation pump is adapted to feed both jet systems.

3. Periodic circuit breaker according to claim 1, characterized in that the feeding of the stationary jets is adapted to take place intermittently and synchronously with the contact closing between corresponding rotating and stationary jets.

4. Periodic circuit breaker according to claim 1, characterized in that the feeding of the stationary jets is adapted to take place intermittently and synchronously with the contact closing between the corresponding rotation and stationary jets, means being provided for interrupting the feeding of contact liquid before the contact between the corresponding stationary and rotating jets is interrupted.

15 5. Periodic circuit breaker according to claim 1, comprising stationary channels for the stationary jets, ejecting nozzles in the inner receptacle adapted to deliver contact liquid to said stationary channels, and distributing channels arranged between said ejecting nozzles and the stationary channels and adapted to receive the liquid from the ejecting nozzles and to discharge the liquid into the stationary channels in the form of drops so as to maintain the liquid supplied through the said ejecting nozzles electrically insulated from the stationary jets.
